FEEDING MECHANISM FOR SEWING MACHINES

Andrew B. Clayton, Elizabeth, N. J., assignor to
The Singer Manufacturing Company, Elizabeth,
N. J., a corporation of New Jersey

Application November 27, 1944, Serial No. 565,213

13 Claims. (Cl. 112—215)

This invention relates to sewing machines and more particularly to sewing machines of the so-called "family" or "domestic" type.

A primary object of the present invention is to render available a relatively small, lightweight, easy running sewing machine adapted to be used selectively for performing any one of a plurality of unlike sewing operations, such, for example, as plain sewing on flat work, plain sewing around either large or small tubular articles, or darning and embroidering on either flat or tubular work.

To enable the machine to sew around small tubular articles it is essential that the machine be provided with a cylindrical work-arm, of relatively small diameter, around which the articles to be sewed may be placed. In sewing machines in which the work-arm contains a loop-taking mechanism and also a work-feeding mechanism, preferably of the four-motioned type, great difficulty heretofore has been experienced in constructing a machine of this nature in which the work-arm is sufficiently small to receive thereon small tubular articles such for example as the legs and sleeves of small children's clothing or small socks and stockings.

I have accomplished this result by providing an improved four-motioned feeding mechanism and so nesting it with the loop-taker mechanism that they may be housed within a cylindrical work-arm of unusually small diameter.

Another object of this invention is to provide an improved work-supporting plate adapted to be removably attached to the cylindrical work-arm of the machine to facilitate use of the machine when performing plain sewing on flat work.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a vertical sectional view of a sewing machine embodying the present invention.

Fig. 2 is a left end view of the machine illustrated in Fig. 1, with the face-plate removed.

Fig. 3 is a transverse sectional view taken substantially on the line 3—3 in Fig. 1.

Figs. 4, 5 and 6 are enlarged transverse sectional views taken substantially on the lines 4—4, 5—5 and 6—6, respectively, in Fig. 1.

Fig. 7 is an enlarged vertical sectional view of the free end portion of the work-arm of the machine, looking in the direction opposite to Fig. 1, showing the loop-taker and a portion of the feeding mechanism of the machine.

Fig. 8 is a detail perspective view of that portion of the feeding mechanism illustrated in Fig. 7.

Fig. 9 is a fragmentary bottom view showing the actuating means for the rotary loop-taker shaft and the feed-drive and feed-lift rock-shafts.

Fig. 10 is a detail perspective view of a flat work-supporting plate adapted to be removably secured upon the work-arm of the machine.

Fig. 11 is a left end view of the machine base and the work-arm showing, in section, the removable work-supporting plate secured thereto.

Fig. 12 is a detail sectional view taken on the line 12—12 in Fig. 11.

Referring more specifically to the drawings, the invention is illustrated as embodied in a lightweight, portable sewing machine having a frame comprising an inverted box-like base 1, a cylindrical work-arm 2 secured to and projecting laterally therefrom, a bracket-arm secured to the base and including a standard 3 and an overhanging arm 4 formed integral with the standard. The bracket-arm terminates in a hollow bracket-arm head 5 which is normally closed by a removable face-plate 6. Journaled lengthwise in the bracket-arm is a main or needle-bar driving shaft 7 carrying at its rear end, a combined belt- and hand-wheel 8 which may be driven from any suitable source of power, such, for example, as by an electric motor M secured upon a rearward extension 1^a of the base 1. At its forward end the shaft 7 has secured to it a crank-disk 9 carrying a crank-pin 10, which, through a link 11 and collar 12, transmits reciprocatory motions to a needle-bar 13 slidably mounted in bearings 14 and 15 in the head 5. At its lower end, the needle-bar 13 carries an eye-pointed needle N which, in the formation of stitches, cooperates with a loop-taker L, later to be referred to, located in the work-arm 2. Also mounted in the head 5 is a spring-depressed presser-bar 16 carrying, at its lower end a presser-foot P. A throat-plate T is secured upon the forward end of the work-arm and is provided with the usual needle-hole n and feed-dog slots f.

The loop-taker L is secured upon the forward end of a rotary loop-taker shaft 17 journaled axially of the work-arm 2 in bearings 18 and 19 carried, respectively, by the arm 2 and the

base 1. The loop-taker shaft is driven, at a ratio of 2 to 1, from the main shaft 7 through the medium of bevel gears 20, 21, a shaft 22 journaled lengthwise within the standard 3, and a pair of bevel gears 23, 24. Thus the loop-taker is given two rotations for each complete reciprocation of the needle N.

One of the important features of the present invention is the construction and arrangement of an improved four-motioned work-feeding mechanism adapted to be embodied in the work-arm of relatively small diameter. This feeding mechanism comprises a feed-dog 25 carried by an upright feed-bar 26 supported upon a floating stud 27. The element 26 is of arcuate shape to fit within the work-arm and avoid contact with the shaft 17 and its forward bearing. The stud 27 is supported in the forked free end 28^a of a feed-lift rock-arm 28, having a bifurcated shank secured upon the outer end of a feed-lift rock-shaft 29 journaled in bearings 30, 31 to extend lengthwise within the work-arm 2 below and to the right of the loop-taker shaft 17, as viewed from the free end of the work-arm. The shaft 29 is given oscillatory movements from an eccentric 32, secured upon the main shaft 7, through the medium of a pitman 33 having one end embracing the eccentric 32 and its opposite end pivotally connected at 34, to an arm 35 projecting laterally from a feed-drive rocker 36 journaled in the base 1. The rocker 36 also has secured to it a longitudinally slotted arm 37 to which is adjustably connected one end of a link 38, the opposite end of which link is pivotally connected to an arm 39 clamped upon the feed-lift rock-shaft 29. The amplitude of movement transmitted to the shaft 29 from the eccentric 32, and thereby the amount of vertical movement transmitted to the feed-bar 26 and the feed-dog secured thereto, may be varied by shifting the point of connection between the arm 37 and the link 38.

Substantially parallel forward and backward, or feed and return, movements are given to the feed-bar 26 and feed-dog 25, in timed relation to their upward and downward movements, by a feed-drive rock-shaft 40 journaled in a long bearing 41 within the work-arm 2, above and to the left of the loop-taker shaft 17, as viewed from the free end of the work-arm. The shaft 40 is oscillated from a cam 42 secured upon the shaft 7 through mechanism comprising an oscillatable and endwise movable lever 43, pivoted, at 44, to an arm 45 projecting from a feed-drive rocker 46 journaled in the base 1. The lever 43 is formed with a forked upper end 43^a which straddles and engages the cam 42. Thus rotation of the shaft 7 and cam 42 effect oscillatory movements of the lever 43 about its pivot 44. These oscillatory movements are translated into endwise movements of the lever by the action of a roller stud 47 carried by the lever and tracking the walls of a slot 48 formed in a tiltable block 49 pivotally secured to the standard 3 by a screw 50. A hand lever 51 connected to the block 49 affords means for tilting the block to vary the amplitude and direction of movement of the lever 43 and consequently the amplitude and direction of the feeding movements of the feed-dog.

The rocker 46 also carries an upstanding arm 52 to which is pivotally connected one end of a link 53; the other end of which link is pivotally connected to an arm 54 secured to and extending downwardly from the rear end of the feed-drive

rock-shaft 40. At its forward end, the shaft 40 carries a depending arm 55, the lower end of which is forked and straddles the stud 27, before mentioned. Thus oscillations of the shaft 40 effect back and forth lateral movement of the stud 27 and the lower end of the feed-bar 26 journaled thereon; the stud 27 sliding sideways in the forked end 28^a of the feed-lift rock-arm 28. The upper end of the feed-bar is given similar back and forth movements, thereby to transmit substantially parallel feed and return movements to the feed-bar and the feed-dog carried thereby, by means now to be described.

Pivots connected to the arm 55 intermediate its ends, by a stud 56, is one end of a curved link 57, the other end of which carries a stud 58 journaled in a boss 59 projecting laterally from the mid-portion of a rock-arm 60. The rock-arm 60 is formed integral with a sleeve 61 which is journaled, for oscillatory motion, on the feed-lift rock-shaft 29. At its upper end, the arm 60 carries a boss 62, in which is journaled a stud 63 projecting laterally from one end of a link 64. The other end of the link 64 carries an oppositely projecting stud 65 journaled in a bore 66 in the upper end of the feed-bar 26.

Upon oscillation of the feed-drive rock-shaft 40, the forked lower end of the arm 55 moves the stud 27 and the lower end of the feed-bar 26 back and forth transversely of the work-arm 2. Similar movements are transmitted from the arm 55 to the upper end of the feed-bar through the link 57, arm 60 and link 64. Thus the entire feed-bar 26 and the feed-dog 25 carried thereby are given feed-and-return movements in substantially parallel horizontal planes in timed relation with the rising and falling movements transmitted thereto from the feed-lift rock-shaft 29.

When fitted as above described, the machine is adapted to perform plain stitching on either flat or tubular work. To facilitate use of the machine in doing plain sewing on flat work I have provided an auxiliary work-supporting plate, of substantial size, which is adapted selectively to be secured upon, or removed from the work-arm. When the plate is secured to the work-arm, its upper surface is substantially flush with the upper surface of the throat-plate T and affords a relatively large work-supporting area. This auxiliary work-support, designated W, is shown detached from the machine in Fig. 10 and as secured upon the work-arm in Fig. 11. As shown most clearly in Fig. 10 the auxiliary work-support 55 is provided with a substantially square aperture 67 adapted to receive the throat-plate T which, as shown in Figs. 1 and 7, projects upwardly from the upper surface of the work-arm. Adjacent its right edge, the auxiliary work-support is provided with two lugs 68 each carrying a pointed dowel pin 69 adapted to enter a dowel hole 70 formed in the base 1 to locate the auxiliary work-support on the machine base and work-arm. Depending from the under side of the auxiliary work-support is a substantially U-shaped bracket, or stirrup, 71 which straddles the work-arm 2 and carries a thumb-screw 72 designed to be adjusted into contact with the under side of the work-arm, thereby to draw the work-support 70 downwardly into firm contact with the upper face of the work-arm.

The above described machine may also be adapted for darning operations and the like on either flat or tubular work by securing to the 75 machine, above the throat-plate, a feed cover-

plate of any suitable or preferred form, such, for example, as a feed-cover plate of the type illustrated in United States patent to Stafford, No. 937,112, Oct. 19, 1909.

From the foregoing it will be perceived that I have provided a sewing machine capable of performing both plain sewing and darning or like operations on either flat or tubular work. Furthermore, it will be perceived that I have provided an improved form of four-motioned feeding mechanism in which the feed and return movements are in substantially parallel horizontal planes and which is adapted to be embodied in a tubular work-arm of relatively small diameter.

Having thus set forth the nature of the invention, what I claim herein is:

1. A work-feeding mechanism for sewing machines comprising a feed-drive shaft; a feed-lift shaft; means to actuate said shafts; an upright feed-bar; a feed-dog carried by said feed-bar; means actuated by said feed-drive shaft and connected to the upper and lower ends of said feed-bar for giving to the feed-bar and the feed-dog carried thereby feed and return movements; and means actuated by said feed-lift shaft and connected to said feed-bar to give to the feed-bar up and down movements in timed relation with its feed and return movements.

2. A work-feeding mechanism for sewing machines comprising a feed-drive shaft; a feed-lift shaft; means to actuate said shafts; an upright feed-bar; a feed-dog carried by said feed-bar; a first rock-arm carried by said feed-drive shaft and connected to one end of said feed-bar; a second rock-arm journaled on said feed-lift shaft; means to actuate said second rock-arm; a link connecting said second rock-arm with the other end of said feed-bar, said rock-arms giving to the feed-bar and the feed-dog carried thereby feed and return movements; and means actuated by said feed-lift shaft and connected to said feed-bar to give to the feed-bar up and down movements in timed relation with its feed and return movements.

3. A work-feeding mechanism for sewing machines comprising a feed-drive rock-shaft; a feed-lift rock-shaft; means to oscillate said shafts; an upright feed-bar; a feed-dog carried by said feed-bar; a first rock-arm carried by said feed-drive shaft and connected to one end of said feed-bar, a second rock-arm journaled on said feed-lift shaft; a link connection between said rock-arms for actuating one from the other, an operative connection between said second rock-arm and the other end of said feed-bar, said rock-arms giving to the feed-bar and the feed-dog carried thereby feed and return movements; and a third rock-arm carried by said feed-lift shaft and connected to said feed-bar to give to the feed-bar up and down movements in timed relation with its feed and return movements.

4. A work-feeding mechanism for sewing machines comprising a feed-drive rock-shaft; a feed-lift rock-shaft; a first rock-arm carried by said feed-lift rock-shaft and having a slotted free end; a stud slidingly mounted in the slotted end of said rock-arm; an upright feed-bar having its lower end mounted on said stud; a feed-dog carried by said feed-bar; a second rock-arm carried by said feed-drive rock-shaft and having its free end engaging said stud; a third rock-arm journaled coaxial with said feed-lift shaft; means to actuate said third rock-arm from said second

rock-arm; a driving connection from said third rock-arm to the upper end of said feed-bar; means to actuate said feed-drive shaft to give to said feed-bar feed and return movements; and means to actuate said feed-lift shaft to give to the feed-bar rising and falling movements in timed relation with its feed and return movements.

5. A sewing machine comprising a frame including a work-arm and an overhanging bracket-arm; stitch-forming mechanism including an eye-pointed needle mounted for reciprocation in said bracket-arm and a complemental loop-taker in said work-arm; and work-feeding mechanism including an upright feed-bar, a feed-dog carried by said feed-bar, a feed-drive shaft and a feed-lift shaft each journaled within said work-arm, means actuated by said feed-drive shaft and engaging the upper and lower ends of said feed-bar to give to said feed-bar feed and return movements, and means actuated by said feed-lift shaft to give to said feed-bar rising and falling movements in timed relation with its feed and return movements.

6. A sewing machine comprising a frame including a cylindrical work-arm and an overhanging bracket-arm; stitch-forming mechanism including an eye-pointed needle mounted for reciprocation in said bracket-arm and a complemental loop-taker in said work-arm; and work-feeding mechanism including an upright feed-bar, a feed-dog carried by said feed-bar, a feed-drive shaft and a feed-lift shaft each journaled within said work-arm, a rock-arm carried by said feed-drive shaft, an operative connection between said rock-arm and one end of said feed-bar, a second rock-arm journaled coaxial with said feed-lift shaft, means to actuate said second rock-arm, an operative connection between said second rock-arm and the other end of said feed-bar, said rock-arms and operative connections giving to said feed-bar feed and return movements, and means actuated by said feed-lift shaft to give to said feed-bar rising and falling movements in timed relation with its feed and return movements.

7. A sewing machine comprising a frame including a base, a hollow work-arm projecting therefrom and a bracket-arm supported from said base and overhanging said work-arm; a main shaft journaled in said bracket-arm; stitch-forming mechanism actuated from said main shaft and including a reciprocating eye-pointed needle and a complemental loop-taker; work-feeding mechanism including a feed-drive shaft and a feed-lift shaft each journaled in said work-arm; means to actuate said feed-lift and feed-drive shafts from said main shaft; an upright feed-bar in said work-arm; a feed-dog carried by said feed-bar; a first rock-arm carried by said feed-drive shaft and operatively connected to one end of said feed-bar; a second rock-arm journaled in said work-arm; a link connection between said rock-arms whereby the second is actuated from the first; a link connection between said second rock-arm and the other end of said feed-bar, said rock-arms transmitting to said feed-bar feed and return movements; and means actuated by said feed-lift shaft to give to said feed-bar rising and falling movements in timed relation with its feed and return movements.

8. A sewing machine comprising a frame including a base, a hollow work-arm projecting therefrom and a bracket-arm supported from said base and overhanging said work-arm; a main

shaft journaled in said bracket-arm; stitch-forming mechanism actuated from said main shaft and including a reciprocating eye-pointed needle and a complemental rotary loop-taker; work-feeding mechanism including feed-drive and feed-lift shafts journaled in said work-arm at opposite sides of the axis of rotation of said loop-taker; means to actuate said feed-lift and feed-drive shafts from said main shaft; an upright feed-bar in said work-arm; a feed-dog carried by said feed-bar; a first rock-arm carried by said feed-drive shaft and operatively connected to one end of said feed-bar; a second rock-arm journaled on said feed-lift shaft; a link connection between said rock-arms whereby the second is actuated from the first; a link connection between said second rock-arm and the other end of said feed-bar, said rock-arms transmitting to said feed-bar feed and return movements; and means actuated by said feed-lift shaft to give to said feed-bar rising and falling movements in timed relation with its feed and return movements.

9. A sewing machine comprising a frame including a base, a hollow work-arm projecting therefrom and a bracket-arm supported from said base and overhanging said work-arm; a main shaft journaled in said bracket-arm; stitch-forming mechanism actuated from said main shaft and including a reciprocating eye-pointed needle and a complemental rotary loop-taker; work-feeding mechanism including a feed-drive shaft journaled in said work-arm above and at one side of the axis of rotation of said loop-taker and a feed-lift shaft journaled in said work-arm below and at the opposite side of the axis of rotation of the loop-taker; means to actuate said feed-lift and feed-drive shafts; an upright feed-bar in said work-arm; a feed-dog carried by said feed-bar; a first rock-arm carried by said feed-drive shaft and operatively connected to one end of said feed-bar; a second rock-arm journaled in said work-arm; a link connection between said rock-arms whereby the second is actuated from the first; a link connection between said second rock-arm and the other end of said feed-bar, said rock-arms transmitting to said feed-bar feed and return movements; and an arm carried by said feed-lift shaft and connected with said feed-bar to give to the feed-bar rising and falling movements in timed relation with its feed and return movements.

10. A sewing machine comprising a frame including a base, a hollow work-arm projecting therefrom and a bracket-arm supported from said base and overhanging said work-arm; a main shaft journaled in said bracket-arm; stitch-forming mechanism actuated from said main shaft and including a reciprocating eye-pointed needle and a complemental rotary loop-taker; work-feeding mechanism including a feed-drive shaft journaled in said work-arm above and at one side of the axis of rotation of said loop-taker and a feed-lift shaft journaled in said work-arm below and at the opposite side of the axis of rotation of the loop-taker; means to actuate said feed-lift and feed-drive shafts, an upright feed-bar in the outer end portion of said work-arm; a feed-dog carried by said feed-bar; a first rock-arm carried by and depending from said feed-drive shaft and operatively connected to the lower end of said feed-bar; a second rock-arm journaled coaxially with

and extending upwardly from said feed-lift shaft, a link connection between said rock-arms whereby the second is actuated from the first; a link connection between said second rock-arm and the upper end of said feed-bar, said rock-arms transmitting to said feed-bar feed and return movements; and means actuated by said feed-lift shaft to give to said feed-bar rising and falling movements in timed relation with its feed and return movements.

11. A sewing machine comprising a frame including a base, a hollow work-arm projecting therefrom and a bracket-arm supported from said base and overhanging said work-arm; a main shaft journaled in said bracket-arm; stitch-forming mechanism actuated from said main shaft and including a reciprocating eye-pointed needle and a complemental rotary loop-taker; work-feeding mechanism including a feed-drive shaft journaled in said work-arm at one side of the axis of rotation of said loop-taker and a feed-lift rock-shaft journaled in said work-arm at the opposite side of the axis of rotation of the loop-taker; means to actuate said feed-lift and feed-drive shafts; an upright feed-bar in the outer end portion of said work-arm; a feed-dog carried by said feed-bar; a first rock-arm carried by said feed-drive shaft and operatively connected to one end of said feed-bar; a second rock-arm journaled in said work-arm; a link connection between said rock-arms below the axis of rotation of the loop-taker whereby the second is actuated from the first; a link connection above the axis of rotation of the loop-taker between said second rock-arm and the other end of said feed-bar, said rock-arms transmitting to said feed-bar feed and return movements; and means actuated by said feed-lift shaft to give to said feed-bar rising and falling movements in timed relation with its feed and return movements.

12. In a sewing machine having a frame comprising a base, a bracket-arm secured thereto, and a work-arm projecting laterally from said base; a main shaft journaled in said bracket-arm; a work-feeding mechanism comprising a feed-lift shaft and a feed-drive shaft each journaled lengthwise of said work-arm; an upright feed-bar in said work-arm; a feed-dog carried by said feed-bar; means to give to said feed-bar up and down and feed and return movements from said feed-lift and feed-drive shafts, respectively; and means to actuate said feed-lift and feed-drive shafts from said main shaft comprising a feed-lift rocker and a feed-drive rocker each journaled in said base; operative connections between said main shaft and said rockers; an operative connection between said feed-lift rocker and said feed-lift shaft; and an operative connection between said feed-drive rocker and said feed-drive shaft.

13. In a sewing machine having a frame including a horizontally disposed work-arm free at one end, a pair of upright and oppositely directed feed-advance rock-arms journaled in and spaced from each other crosswise of said work-arm, means for actuating said rock-arms in unison, a horizontally disposed feed-lift rock-arm, a vertically disposed feed-bar connected to said feed-lift rock-arm for movement therewith and relatively thereto, and operative connections between the opposite ends of said feed-bar and said feed-advance rock-arms.

ANDREW B. CLAYTON.
